UNITED STATES PATENT OFFICE

94,947

DESIGN FOR A CIGARETTE AND CIGAR ASH RECEPTACLE

Willi Conrad, Berwyn, Ill.

Application December 24, 1934, Serial No. 54,821

Term of patent 3½ years

To whom it may concern:

Be it known that I, Willi Conrad, a citizen of Germany, and resident at Berwyn, Cook County, Illinois, have invented a new, original, and ornamental Design for Cigarette and Cigar Ash Receptacles, of which the following is a specification, reference being had to the accompanying drawing, forming part thereof.

Fig. 1 is a side elevational view of my design.

Fig. 2 is a front elevational view of my design.

Fig. 3 is a rear elevational view of my design.

I claim:

The ornamental design for a cigarette and cigar ash receptacle as shown in the drawing.

In witness whereof, I have hereunto set my hand and seal this 27th day of November, A. D. 1934.

WILLI CONRAD.
